JAMES K. P. NOURSE, OF WEST MEDWAY, MASSACHUSETTS.

Letters Patent No. 83,993. dated November 10, 1868.

IMPROVEMENT IN BOILER-FEED-WATER REGULATORS.

The Schedule referred to in these Letters Patent and making part of the same

To all to whom these presents shall come:

Be it known that I, JAMES K. P. NOURSE, of West Medway, in the county of Norfolk, and State of Massachusetts, have invented a new and useful Automatic Feed-Water Regulator for Steam-Generators; and do hereby declare the following to be a full, clear, and exact description thereof, due reference being had to the accompanying drawing, which is a section of such invention.

The object of this invention is to provide a device for attachment to steam-boilers, for the purpose of insuring a supply of water to such boiler, and maintain it at a proper level therein, as well as to give warning if, by accident, this supply of water is cut off from the boiler.

The invention consists in the combination, with an ordinary pump and steam-boiler, of a series of pipes and a steam and water-vessel, communicating with the water-space of the boiler, and provided with a float for regulating the supply of feed-water to the pump, in such manner that, should the water in the boiler fall below the proper level, the float in the vessel will open communication to the pump, and, by supplying it with water, cause such pump to force the water into the boiler and replenish its supply, and when the water in the boiler has reached the desired level, the ascent of the float shuts off the supply of water to the pump, and consequently to the boiler.

Furthermore, the vessel, float, and feed-pipes are also arranged with respect to a steam-whistle, suitably applied to the boiler, that, should the pump, from any cause, entirely cease to perform its functions, and the water in the boiler and in the auxiliary vessel, fall to or below a certain point, the steam-whistle will sound an alarm, and give timely warning to the attendant of the boiler.

In the drawing above mentioned, as illustrating my invention, B denotes a portion of a steam-boiler, of any ordinary construction, and alongside of which is disposed a hollow closed vessel or float-chamber, C, this vessel communicating with the water-space of the boiler by a pipe, b, leading out of its lower part, by which means the water will stand upon an equal level in the vessel and the boiler.

A steam-whistle, H, of ordinary construction, is applied to the top of the vessel C, and communicates with the steam-space of the boiler by a lateral pipe, a, the point of communication of this pipe with the whistle being controlled by a lever, h, properly pivoted to the under side of the top of the vessel C, the free end of such lever being connected, by a chain or other means, to a float disposed within such vessel, and buoyed upon the water contained therein.

P, in the drawing, denotes a force-pump of any well-known construction, its discharging-pipe, for feeding the boiler with water, being shown, at f, as extending into the lower part of such boiler. The supply-pipe of the pump P is shown, at d, as communicating with a suitable tank or other water-receptacle, such pipe d extending upward through the bottom of the vessel C, and into the interior thereof, where it is given a siphon-shaped bend, and carried back downward through the bottom of such vessel C, and thence carried to the pump P, the portion of the siphon within the float-chamber C being provided with a cock or gate for regulating the supply of water to the pump.

Within the chamber or vessel C, and buoyed upon the water contained therein, is a float, F, of proper construction, this float being connected to the cock or gate g by a lever, e, or other device, in such manner that, should the water in the boiler be raised above the level at which it is desirable to maintain it, the rising of the float with the water will close the gate and shut off the supply of water to the pump, which will continue to run without throwing water.

Should the water fall below the proper point in the boiler, and, as a consequence, in the vessel C, the lowering of the float with the water will open the gate g, and allow water to flow through the pipe d and supply the pump.

Should the pump, by any accident, be disabled, or unable to force water to the boiler, and the water in such boiler fall to an improper or a determined point, the fall of the float F to this point will depress the lever h, and by this means open communication between the steam-space of the boiler and the whistle H, and sound an alarm.

Having now described my invention, and the manner in which the same is or may be carried into effect, What I claim, and desire to secure by Letters Patent, is—

1. The combination, with the vessel C and float F, of the pump P, the bent pipe d, and its gate g, contained within the said vessel, and connected to the said float, the whole being arranged substantially as herein shown and specified.

2. In combination with the arrangement of parts claimed in the preceding clause, I claim the steam-whistle H, pipe a, and lever h, connected with the float F, as specified, the whole being arranged substantially as herein shown and set forth.

JAMES K. P. NOURSE.
